UNITED STATES PATENT OFFICE.

DAVID H. FANNING, OF WORCESTER, ASSIGNOR TO THEODORE C. BATES,
OF NORTH BROOKFIELD, MASSACHUSETTS.

CORSET.

SPECIFICATION forming part of Letters Patent No. 244,573, dated July 19, 1881.

Application filed January 8, 1881. (Model.)

To all whom it may concern:

Be it known that I, DAVID H. FANNING, of Worcester, county of Worcester, and State of Massachusetts, have invented a new and useful Improvement in Corsets, of which the following description, in connection with the accompanying drawings, is a specification.

This invention relates to corsets, and has for its object to provide a very stiff corset at 10 and along the central portion of the corset at its sides.

My invention consists in making the sides of the corset at its central portion of three or more thicknesses or layers of cloth stitched 15 together to form at least two series of pockets, one above the other, to receive at least two series of superimposed bones or stiffening-strips, each bone being in a separate pocket. In this instance of my invention I have shown 20 the stiffened sides of the corset containing vertical bones as not extended to the bottom or to the top of the said corset at its sides; but above and below the top of the said stiffened side pieces I have placed and united into and 25 so as to form part of the corset suitable hip and arm-size strips or sections composed of several stiffened layers of cloth, preferably four or more such layers, held together by stitching or quilting.

30 Figure 1 represents, in side elevation, a sufficient portion of a corset to illustrate my present invention. Fig. 2 is a section thereof on the line $x-x$, and Fig. 3 is a partial vertical section taken through the arm-size section on line y , it being understood that a like view of the hip-section would show a like arrangement of layers of material, preferably cloth.

The front piece, a , and back piece, b , of the corset may be of any usual shape. The side 40 piece is divided up, as hereinafter described, so as to form a hip-strip, c , an arm-size section, d , and waist-section e .

The waist-section e (see Fig. 2) is composed of three thicknesses of cloth stitched together at suitable intervals, as at 2, to form a 45 double series of pockets, 3 4, to receive independent bones or stiffening-strips $f g$, which are so inserted in the said independent pockets as to be superimposed one on the other, 50 thus giving additional stiffness to the waist-section and greatly reducing its liability to bend in a direction transverse to the length of the said bones $f g$. The waist-section e termi-

nates, it is seen, short of the lower and upper ends of the front and back pieces, $a b$.

At the lower end of the waist-section e , I have placed what I denominate a "hip-strip" or "section," the said section being composed of several thicknesses of cloth, preferably more than four thicknesses, stitched together, as at 60 h , by numerous lines of stitches, thus adding to the stiffness of the said section e . The ends of the section e are connected or stitched to the front and back pieces, $a b$.

The arm-size section d , composed in a like 65 manner of several thicknesses or layers of cloth stitched together by numerous lines of stitches, (see sectional detail, Fig. 3,) is joined at its ends by stitches with the front and back pieces, $a b$.

I may, if desired, employ between the outer and inner layers of cloth forming the hip-section h and the arm-size section d any usual well-known stiffening material.

I claim—

1. In a corset having front and back pieces, $a b$, the waist-section provided with a parallel series of double pockets, and with two series of superimposed bones or stiffening-strips, each inserted in its own independent pocket, substantially as described.

2. The front and back pieces, $a b$, of the corset and the stiffened waist-section connected therewith, combined with the arm-size section, connected at its ends with the pieces 85 $a b$, and at its lower edge with the waist-section, and stitched and stiffened, as shown and described.

3. The front and back pieces, $a b$, of the corset, combined with the stiffened waist-section and arm-size and hip sections connected with the upper and lower edges of the said waist-section, and stitched and stiffened, as shown and described, the ends of the said waist, arm-size, and hip sections being secured at their 95 ends with the pieces $a b$, as shown and described.

4. The combination, in a corset, of a sheet of fabric with pockets on opposite sides thereof containing stiffening-ribs.

In testimony whereof I have signed my name to this specification in the presence of two subscribing witnesses.

Witnesses: DAVID H. FANNING.
